R. G. HALLOCK

CARBURETOR ADJUSTER AND GASOLINE LINE LOCKING DEVICE

Filed Dec. 26, 1923

INVENTOR
Raymond G. Hallock
Harry Bowen
ATTORNEY

UNITED STATES PATENT OFFICE.

RAYMOND G. HALLOCK, OF BREMERTON, WASHINGTON.

CARBURETOR ADJUSTER AND GASOLINE-LINE-LOCKING DEVICE.

Application filed December 26, 1923. Serial No. 682,706.

The invention is a means for adjusting the carburetor from the instrument board of a motor vehicle which may also be used to shut off and lock the gasoline supply line.

5 The object of the invention is to provide a simple and efficient means for adjusting the carburetor of a motor vehicle which may be operated from the instrument board.

Another object of the invention is to provide 10 a means for adjusting the carburetor from the instrument board which may be made of one piece of material.

And a further object of the invention is to provide 15 a means for adjusting the carburetor from the instrument board which may also be used to lock the gasoline supply line, either entirely closed or in different adjustments.

With these ends in view the invention embodies 20 a curved bar having a handle at one end, two prongs at the other, and a loop for holding it.

Other features and advantages of the invention will be seen from the following description taken in connection with the drawings, wherein:—

Figure 1 is a sectional view showing the device.

Figure 2 is a section showing an alternate 30 arrangement in which a block of wood is shown behind the instrument board which is common in enclosed vehicles.

Figure 3 is a view showing another alternate arrangement.

Figure 4 is a view showing an alternate arrangement in which a loop is provided in the bar so that it may be lengthened or shortened.

Figure 5 is an alternate design showing 40 the lower end of the bar flattened and placed in a slot in the upper end of the carburetor adjusting stem.

Figure 6 is a view showing an alternate arrangement in which the lower end of the bar is flattened and placed between two flat plates at the upper end of the carburetor adjusting stem.

Figure 7 is a view showing an alternate arrangement in which the bar is flattened and bolted to the upper end of the carburetor adjusting stem.

Figure 8 is a view showing an alternate arrangement in which the loop 8 bears against a bracket at the dash board.

55 Figure 9 is a view showing an alternate

arrangement in which a section of the dash board is stamped on an angle.

In the drawings I have shown my device as it would be constructed wherein numeral 1 indicates the bar, numeral 2 a carburetor, 60 and numeral 3 an instrument board.

The bar 1 may be constructed as shown and curved so that it will pass directly backward from the instrument board, 65 through an opening 4 in the dash board 5 and then curved downward so that it will come directly down on the axis of the needle

valve of the carburetor. The upper end of the bar extends through an opening 6 in the instrument board and is then bent at an 70

angle to form a handle 7. The bar may be provided with a loop 8 which may bear against the under side of the instrument board as shown in Figure 1 and this loop which may be welded at the point of intersection of the bars may be arranged so that the yoke of a lock may pass through it and through an opening 9 in the instrument board which will make it possible to 75 lock the device at the instrument board.

This loop may also be placed in a position adjacent the dash board 5 so that it may bear against the under side of a bracket 10 as shown in Figure 8 so that the rod may be held downward from the dash board. 80

It is also understood that the bracket 10 may be omitted and a section of the dash board stamped on an angle as shown in Figure 9 and indicated by the numeral 11 so that the yoke 8 may bear against its under 85

side in order to hold the bar downward. The lock shown in Figure 1 may be used to lock the bar 1 through the loop 8 in either of the designs shown in Figures 8 90

and 9 by placing the yoke of the lock 95 through the loop and through openings in the bracket or dash board.

The designs shown in Figures 2 and 3 comprise alternate arrangements for holding the upper end of the bar at the instrument 100 board. In Figure 2 the loop 8 is replaced by a U bend 12 which is particularly adaptable

for enclosed cars but may be used with the type of instrument board shown in Figure 1. It will be seen that the lock may be used 105

with this design by placing the yoke through the U bend and through an opening 9 in the instrument board. In Figure 3 a straight bar 13 is used for holding the bar 1 upward, and this bar is rigidly attached to the bar 1 110

and slightly curved at the ends so that its ends will bear against the under side of the instrument board. It is understood that either of these designs may be used for holding the upper end of a bar or any other suitable means may be used.

The lower end of the bar 1 is provided with prongs 14 which may be placed through openings in a plate 15 at the upper end of the 10 needle valve stem of the carburetor. Or this end may be held in place by a lock 16 as shown in Figure 1. A loop 17 as shown in Figure 4 may be provided at the lower end of the bar so that it will be possible to 15 lengthen or shorten the bar by increasing or decreasing the size of the loop. This loop may also be used to lock the device as the lock 16 may be placed through it as shown.

In Figures 5, 6, and 7 I have shown alternate means for attaching the lower end of the bar 1 to the needle valve stem. In each of these designs the lower end of the bar 1 is flattened as shown and this flattened section, as indicated by the numeral 18, may be 25 placed through a slot in the bar 15 as shown in Figure 5, or placed between two flat plates 19 as shown in Figure 6, or bolted to a flat section 20 at the upper end of the valve stem by bolts 21 as shown in Figure 7. The 30 section 18 may be provided with an opening 22 in the design shown in Figure 5 so that a pin or lock may be placed through it to hold it in place. A similar opening 23 may be placed through the flat sections shown in 35 Figures 6 and 7 so that pins or locks may be placed through them to hold them in place. It is also understood that either of the designs shown or any other suitable means may be used for holding the lower end of the bar 40 to the needle valve stem.

The construction will be readily understood from the foregoing description. To use the device it may be installed in a car by placing the rod 1 through an opening 45 in the dash board, attaching its lower end

to the needle valve stem of the carburetor in any suitable manner and attaching its upper end to the instrument board in any suitable manner. It will then be seen that by turning the handle 7 of the bar it will be 50 possible to rotate the needle valve. And it will also be seen that the needle valve may be adjusted to any suitable position, which may provide a proper mixture or which may close the valve, and that the lower end of 55 the rod may be attached to the stem in such a manner that when the valve is closed the upper end of the rod will be in the position shown so that the lock may hold it. This will make it possible to lock the needle 60 valve in a plurality of open positions or completely closed as may be desired. By removing the lock at the upper end it will be possible to adjust the carburetor from the instrument board by twisting the handle 7. 65

Having thus fully described the invention what I claim as new and desire to secure by Letters Patent, is:

1. A means for adjusting and locking the carburetor of a motor vehicle from the instrument board comprising a curved bar having prongs for connecting it to the needle valve stem, a loop adjacent its upper end, a handle at its upper end and suitable locks for locking the prongs to the carburetor 75 and the loop to the instrument board.

2. A means for adjusting the carburetor of a motor vehicle from the instrument board comprising a bar having projections at the lower end that may be placed in the opening at the top of the needle valve stem; a handle at its upper end which may project through the instrument board; a means for holding the upper end to the instrument board; and suitable means for locking the lower end to the carburetor and also for locking the upper end to the instrument board.

RAYMOND G. HALLOCK.
